UNITED STATES PATENT OFFICE.

ANSON E. BOWER, OF HUDSON, NEW YORK.

HAMPER.

1,181,829.

Specification of Letters Patent.

Patented May 2, 1916.

Application filed August 13, 1914. Serial No. 356,640.

To all whom it may concern:

Be it known that I, ANSON E. BOWER, a citizen of the United States, residing at Hudson, in the county of Columbia and State of New York, have invented certain new and useful Improvements in Hampers; and I do hereby declare the following to be a full, clear, and exact description of the invention, such as will enable others skilled in the art to which it appertains to make and use the same.

This invention relates to folding hampers, and one of the principal objects of the invention is to provide a hamper of light construction which can be utilized for containing parcel post packages or for other goods and which can be returned in flat and folded condition, thus occupying but little space.

Another object of the invention is to provide a hamper comprising a folding frame covered with canvas or other suitable material and provided with a rigid board or bottom to hold the device extended, and said board being foldable up against one of the sides when not required for use, and the frame being foldable centrally and longitudinally and provided with straps for holding the cover in place and for holding the hamper folded.

These and other objects may be attained by means of the construction illustrated in the accompanying drawings, in which,

Figure 1 is a perspective view of a hamper, made in accordance with this invention and shown in closed condition, Fig. 2 is a top plan view of the frame of the hamper in folded condition, the cover being removed, Fig. 3 is a perspective view of the frame of the hamper in opened out condition, Fig. 4 is a detail view of one of the staples, Fig. 5 is an edge view of the frame and base board hinged to one of the side members and adapted to be folded against the bottom or side of the frame, and Fig. 6 is a detail view of one of the pivoted straps for holding the cover in place and for holding the hamper in collapsed or folded condition.

Referring to the drawings, the numerals 1 designate the longitudinal bottom rods, 2 are the upper rods of the frame. These rods are pivotally connected to corner posts 3 and 4. The ends of the rods are flattened as shown in Fig. 3. The end bars 5 at the top and bottom of the frame are pivotally mounted at their outer ends upon the ends of the corner posts 4 and their inner ends are

connected together and pivoted to the centrally disposed upright rods 6. Hinged to one of the longitudinal rods 1 by means of a metal strap 7 near each end is a board 8 which conforms substantially to the rectangular area of the bottom of the hamper. This bottom board 8 is provided upon one side with a pair of staples 9, and connected to said staples are straps 10.

The hamper is covered with strong fabric such as canvas, and the cover is made up of a size to properly fit over the metal frame work. The covering 11 may be provided with a suitable handle 12 at the end. 70 The top or cover 13, also of canvas or other suitable fabric is provided with a tubular portion to fit over one of the rods 2, and said cover being provided with down-turned rectangular flanges 14 provided with a series of openings through which extend the staples 15. The staples 15 are secured to the covering 11 by means of base plates 16 and 17, one upon each side of the material of the cover. At the center of the 80 covering 11 is a staple 18 bent at right angle to the staples 15. Straps 19 are pivoted at the back of the hamper in line with the top or cover 13 on rivets 20 extending through the canvas material 11 and through suitable washers 21 and 22. The staples 15 and 18 extend through slots in the top or cover 13. The straps 19 extend around through the staples and are connected to the front staple 18, as shown in Fig. 1. 90

An address card holder 18^a is attached to the staple 18 after the straps 19 have been connected therewith. At the back the straps 19 are each provided with a suitable buckle 23 connected to the straps 19 by means of a short billet 24. When the hamper is folded, the straps 19 extend around transversely for holding the parts together flat, and the pivots 20 permit this movement of the straps 19, the buckle 23 carried 100 by the straps 19 at a point adjacent the pivotal point being adapted to receive into the slot when the member is in a folded position.

The manner of folding the hamper may 105 be briefly described as follows: The bottom board 8 is released by unbuckling the straps 10 from the buckles ^a which are secured to straps pivoted to the upper portion of the cover and doubling the board 8 against 110 the back of the hamper. The end members are then pushed inward and the top and

bottom bars 1 and 2 fold inward as shown in Fig. 2 of the drawing. The top or cover 13 is first removed or disconnected by withdrawing the straps 19 from the staples 15. 5 When the hamper is collapsed or folded together, the straps 19 are turned at right angles upon the pivots 20 to extend around the folded hamper.

From the foregoing it will be obvious 10 that a hamper made in accordance with this invention is simple in construction, can be used to advantage in carrying parcel post packages or for shipping goods to be re-turned in folded condition.

15 Various changes may be made in the details of construction without departing from the spirit and scope of the invention as defined in the claims.

What is claimed is:—

20 1. A hamper made up of metal rods at the top and bottom connected to corner posts and end members pivoted to the corner posts and to separate centrally disposed uprights, a fabric covering for the body 25 of said hamper, and a top or cover connected to one of the longitudinal bars, a series of staples secured to the fabric covering and extending through slots in the top, straps pivoted at the back of the hamper and adapted 30 to extend through said staples, and a bottom board hinged to one of the longitudinal bars and means to hold the board in position.

2. A hamper comprising longitudinal

top and bottom rods, corner posts to which 35 said rods are pivoted, end members pivoted to the corner posts, central upright rods to which said end members are connected, a hinged bottom wall, a fabric covering, a plurality of staples connected to said covering, a top or cover, straps pivoted to the back of a hamper to extend through 40 said staples, said straps adapted to be withdrawn and turned at right angles for holding the collapsed hamper in a folded 45 position, said staples of the covering extending through the cover when assembled.

3. A folding hamper comprising a frame composed of metal rods, corner posts to which 50 said rods are pivoted, end members pivoted to said posts, central vertical rods to which the end members are pivoted, a fabric cover for the body of the hamper, a plurality of staples secured to the fabric cover, a top for said hamper, said top provided at its front edges with a plurality of 55 openings adapted to receive the staples therethrough, straps pivoted to the back of the hamper to extend through said staples, said straps adapted to be withdrawn and 60 turned at right angles for holding the collapsed hamper in a folded position.

In testimony whereof I affix my signature in presence of two witnesses.

ANSON E. BOWER.
